8, 1947, Serial No. 778,681

3 Claims. (Cl. 175—182)

1

The present invention relates to apparatus for investigating earth formations traversed by a bore hole, and more particularly to new and improved apparatus for determining the depth and thickness of permeable formations traversed by a bore hole.

This application is a division of my copending application Serial No. 446,888, filed June 13, 1942, for Method and apparatus for investigating earth formations traversed by a bore hole, now Patent No. 2,433,746, granted December 30, 1947.

The above-mentioned copending application discloses methods and apparatuses for investigating earth formations traversed by a bore hole by means of alternating electro-filtration potentials. The latter potentials are created artificially by producing periodically fluctuating pressure in the bore hole liquid in the vicinity of permeable formations, and they are picked up by electrodes connected to suitable indicating means.

The present application is addressed specifically to one form of apparatus in which mechanical means are employed for producing the periodically fluctuating pressure in the bore hole liquid.

The invention may be better understood from the following detailed description taken in conjunction with the accompanying drawings, in which:

Figure 1 is a schematic diagram in longitudinal section of apparatus constructed according to the invention for producing alternating potentials related to electrofiltration potentials in a bore hole;

Figure 2 illustrates a curve of spontaneous potentials such as might be obtained by means of the apparatus shown in Figure 1;

Figure 3 is a schematic showing of a modified form of the invention; and

Figure 4 shows the type of electrofiltration potential curve produced with the apparatus of Figure 3.

Referring now to Figure 1, the invention is shown embodied in apparatus 10 for producing periodic variations in the pressure of the liquid 11 at the level of a relatively permeable formation 13 traversed by a bore hole 12. It will be assumed in the following description that the pressure of the bore hole liquid 11 is greater than the pressure of any fluid contained in the formation 13, so that electrofiltration potentials will be present. The apparatus 10 comprises preferably a cylindrical water-tight casing 14 containing an electric motor 15 which is adapted to drive, through conventional type gearing 16, a crank arm 17 on which is mounted a weight 18. The 55

2

crank arm 17 is mounted in suitable bearings 19 and 20 for rotation about a vertical axis.

The crank arm 17 drives, through conventional gearing 21, a second crank arm 22, journaled in suitable bearings 23 and 24 for vertical rotation within the casing 14 and having a weight 25 mounted thereon. It will be noted that the gearing 21 causes the crank arms 17 and 22 to rotate in opposite directions, when the motor 15 is in operation.

One terminal of the motor 15 is connected to a conductor 26 in the supporting cable 27, the upper end of which is connected in series with a conventional type switch 28 and a suitable source 15 of electrical energy 29, the other terminal of which is connected to ground at the point 30 at the surface of the earth. The energizing circuit for the motor 15 is completed through the earth and the bore hole liquid 11 and to this end 20 its other terminal is grounded to the body of the apparatus 14 at the point 31. If any interference is encountered between the current and the recording circuits, it may be desirable to use a second conductor in the cable 27 instead of the 25 ground return.

In operation, the switch 28 at the surface of the earth is closed and the apparatus 10 is moved through the bore hole 12. This energizes the motor 15, causing it to drive the crank arms 17 and 22 in opposite directions. The result of this rotation of the weights 18 and 25, respectively, on the crank arms 17 and 22, respectively, is to impart an extremely vigorous vibrating motion to the apparatus 10 in a plane perpendicular to the paper. This vigorous vibration produces periodic increases and decreases in the pressure of the bore hole liquid at opposite sides of the apparatus 10.

As described above, the periodic variation in 40 the pressure of the bore hole liquid 11 as the apparatus passes the formation 13 produces a corresponding periodic variation in the electrofiltration potentials existing in the bore hole 12 in the vicinity of the porous formation 13. These 45 electrofiltration potentials may be measured in any desired manner by any suitable apparatus. Such apparatus may comprise, for example, a relatively small, insulated electrode 32 of any desired shape, mounted on the outside of the casing 14, preferably on a radius perpendicular to a line passing through the centers of the bearings 19 and 23. The electrode 32 may be connected through a conductor 33 in the supporting cable 27 to one terminal of a conventional alternating 50 current potential indicating instrument 34, pref-

erably of the recording type, the other terminal of which may be connected to a ground point 35 at the surface of the earth.

A representative curve such as might be obtained by the recording apparatus 34 is shown in Figure 2, from which it appears that the spontaneous potential curve is modulated in the vicinity of the porous formation 13 at the frequency of vibration of the apparatus 10 in the bore hole. The normal spontaneous potential curve, such as might be obtained with the switch 28 open, is shown in dotted lines for purposes of comparison.

In the embodiment described above, other measuring circuits may be employed for obtaining indications of electrofiltration potentials in a bore hole. For example, in Figure 1, indications of electrofiltration potentials might be obtained by making measurements between the electrode 32 and another electrode 60 located at the same level on the other side of the casing 14 opposite the electrode 32 and connected by a conductor 61 to the recorder 34, as in Fig. 3. This modification produces a curve of alternating electrofiltration potentials alone (Fig. 4). As a further modification, indications might be obtained of the voltages between each of two such electrodes and ground.

The invention thus provides a new apparatus for obtaining indications of electrofiltration potentials apart from other continuous potentials that may be present in a bore hole. By producing a localized and periodically variable pressure variation at different depths in the bore hole, continuous electrofiltration potentials may be changed to alternating potentials that can be readily separated from other continuous potentials which may be encountered. Accordingly, the invention enables accurate indications of electrofiltration potentials to be obtained without taking any special precautions even in wells located in the vicinity of relatively strong telluric currents.

The embodiment described above is intended to be illustrative and not restrictive. Numerous modifications in form and detail may be made in that embodiment within the scope of the following claims.

I claim:

1. In bore hole investigating apparatus, the combination of a body adapted to be lowered into a bore hole containing a liquid, an eccentric mass rotatably mounted in the body, power means for rotating said mass to produce periodic pressure fluctuations in said liquid at a relatively rapid rate above that to which a direct current meter is responsive, thereby generating variable alternating electrofiltration potentials in the vicinity of permeable formations, a first electrode assembled

to said body so as to be movable at substantially the same level therewith, a second electrode located at a position where it is not subject to the same instantaneous pressure as said first electrode, circuit means transmitting to the surface alternating potentials picked up by said electrodes and produced by said generated alternating electrofiltration potentials, and means for providing indications of said alternating potentials.

2. In bore hole investigating apparatus, the combination of a body adapted to be lowered into a bore hole containing a liquid, a pair of eccentric masses rotatably mounted in the body, electrical power means for rotating said masses to produce periodic pressure fluctuations in said liquid at a relatively rapid rate above that to which a direct current meter is responsive, thereby generating variable alternating electrofiltration potentials in the vicinity of permeable formations, a source of electrical energy at the surface, electrical means for energizing said electrical power means from said source, a first electrode assembled to said body so as to be movable at substantially the same level therewith, a second electrode located at a position where it is not subject to the same instantaneous pressure as said first electrode, circuit means transmitting to the surface alternating potentials picked up by said electrodes and produced by said generated alternating electrofiltration potentials, and means for providing indications of said alternating potentials.

3. In bore hole investigating apparatus, the combination of a body adapted to be lowered into a bore hole containing a liquid, an eccentric mass rotatably mounted in the body, power means for rotating said mass to produce periodic pressure fluctuations in said liquid at a relatively rapid rate above that to which a direct current meter is responsive, thereby generating variable alternating electrofiltration potentials in the vicinity of permeable formations, a first electrode assembled to said body so as to be movable at substantially the same level therewith, a second electrode located at substantially the same level as said first electrode and on the opposite side of the body therefrom, said first and second electrodes being so positioned that they are not subjected to the same instantaneous fluid pressure, circuit means transmitting to the surface alternating potentials picked up by said electrodes and produced by said generated alternating electrofiltration potentials, and means for providing indications of said alternating potentials.
